INVENTOR
A. LLOYD.

BY
Fetherstonhaugh Co.

ATTORNEY

UNITED STATES PATENT OFFICE.

ALFRED LLOYD, OF LONDON, ENGLAND, ASSIGNOR TO MILAN FRANCIS PRATT, OF ROCHESTER, NEW YORK.

ELECTRICAL HAIR OR MASSAGE BRUSH.

Application filed April 10, 1926, Serial No. 101,142, and in Great Britain September 18, 1925.

This invention refers to improvements in or relating to electrical hair or massage brushes.

Heretofore it has been proposed to construct electrical hair brushes, with a projecting handle to be grasped by the user, and having the electrical components located in the said projecting handle (or in a separate casing or device arranged to be connected to the brush) the circuit being completed through metallic bristles in the brush and through the hand of the user.

An object (inter alia) of my present invention is to provide a simple and compact form of electrical hair or massage brush without a projecting handle i. e. of the form known as "military" hair brushes; and to this end according to my present invention I arrange and mount the electrical components (such as a battery, trembler coil and if desired a variable resistance) in or on the back of the brush itself in suchwise that when the brush is gripped by the hand of the user and applied to the head or body of the user thereby the electrical circuit is completed, for example when the brush is grasped by the hand of the user (in readiness for use) thereby a press contact or other suitable contact is operated by the said grip or grasp of the hand to render the brush electrically operative when applied to the head of the user.

One form of electrical hair brush of said "military" type in accordance with my present invention is illustrated in the accompanying drawings, in which:—

Fig. 1 is a view in side elevation of the complete brush.

Fig. 2 is a plan view with the top cover or casing removed.

Fig. 3 is a vertical sectional view on the line 3—3 Fig. 2, and

Fig. 4 is circuit diagram of the electrical connections.

Referring to these drawings—

Mounted on the underside of a wooden or other insulating back or base A are a number of metallic bristles B, the heads of which are secured between a metallic plate C and a rubber or like face D. An external ring of ordinary bristles E is provided.

On the upper side of the brush back A is mounted a small dry battery F, one pole of which is earthed at F¹ to a metallic cover G which forms the means by which the

brush is grasped in the hand. The other pole F² of the battery is connected through a metallic plate H to an adjusting screw J forming the contact for an armature K of a trembler coil L, one end of the primary winding of which is connected to the armature K whilst the other end is earthed to the cover G through the press button switch M, which is conveniently located for operation by the fingers when the brush is grasped in the hand and contacts when pressed inwardly with the metallic piece M¹ in electrical connection with the cover G.

The secondary winding of the coil L is tapped at three points whence leads L¹, L² and L³ are taken to three studs over which works the switch arm M operated by a finger piece O projecting through the top of the cover G.

The switch arm M is electrically connected to a spring plate P pressing on a contact Q which is in electrical connection with the plate C and consequently with the metallic bristles B. The other end of the secondary winding is earthed to the cover at R.

The cover G is made detachable from a metal rim A¹, secured to the brush back A, by means of a thumb button S which when pressed releases a catch S¹ from an aperture in the rim A¹.

To use the brush the three-way switch M is set by means of the finger piece O to give the desired current strength and the brush is then grasped in the hand, the press button contact N being pressed inwardly. Current thereupon flows in the primary circuit which is interrupted by the trembler armature K, thereby inducing a current in the secondary circuit which is completed through the hand and arm of the user.

Thus is provided according to the present invention a simple compact and reliable electrical hair or massage brush of the "military" type in which all of the electrical components are contained in the back of the brush and in a readily accessible manner.

What I claim is:—

1. A "military" type hair brush comprising electrically conductive bristles, a battery mounted on the back of the brush towards one end thereof with one pole of said battery connected through a press contact switch to a detachable metallic cover for the back of the brush and the other pole in contact with a plate in circuit with an adjusting screw.

- for a trembler make and break device, an induction coil mounted on the back of the brush with one pole of the primary winding connected to the armature of the make and break device and the other pole to the said metallic cover, a plurality of tappings from the secondary winding connected to a multiple-way switch with an operating handle projecting through the metallic cover and the latter being connected to the other end of the secondary winding of the induction coil so that in use the secondary circuit is completed through the metallic cover and the hand and body of the user.
15. 2. A "military" type hair brush comprising electrically conductive bristles, a battery mounted on the back of the brush towards one end thereof with one pole of said battery connected through a press contact switch to

a detachable metallic cover for the back of the brush and the other pole in contact with a plate in circuit with an adjusting screw for a trembler make and break device, an induction coil disposed transversely of the brush across the end of the battery with one pole of the primary winding connected to the armature of the make and break device and the other pole to the said metallic cover, a plurality of tappings from the secondary winding connected to a multiple-way switch with an operating handle projecting through the metallic cover and the latter being connected to the other end of the secondary winding of the induction coil so that in use the secondary circuit is completed through the metallic cover and the hand and body of the user.

ALFRED LLOYD
